Primary Examiner — Cathron C Brooks*Assistant Examiner* — W. A. Teddy Falloway(74) Attorney, Agent, or Firm — DLA Piper LLP (US)(57) CLAIM

We claim the ornamental design for a bag, as shown and described.

DESCRIPTION

FIG. 1 is a perspective view of a bag showing our new design;

FIG. 2 is a front elevational view thereof;

FIG. 3 is a rear elevational view thereof;

FIG. 4 is a side elevational view thereof;

FIG. 5 is an elevational view of the other side thereof;

FIG. 6 is a top plan view thereof;

FIG. 7 is a bottom plan view thereof;

FIG. 8 is a perspective view from the top left side of the bag with its top flap open; and,

FIG. 9 is a perspective view from the right side of the bag with its top flap open.

All broken lines are directed to environment and are for illustrative purposes only; the broken lines form no part of the claimed design.

1 Claim, 7 Drawing Sheets(56)
